(57) **CLAIM**

The ornamental design for a shoebox, as shown and described.

DESCRIPTION

FIG. 1 is a perspective view of a shoebox, showing my new design;

FIG. 2 is another perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view thereof, in a condition of use;

FIG. 10 is another perspective view thereof, in an alternate condition of use; and,

FIG. 11 is another perspective view thereof, in an alternate condition of use.

The broken lines in FIGS. 9, 10 and 11 depict environmental structure only that form no part of the claimed design. The remaining broken lines in the drawings depict portions of the shoebox that form no part of the claimed design.

1 Claim, 11 Drawing Sheets
